Patented Oct. 23, 1917.

UNITED STATES PATENT OFFICE.

HENRY F. WORLEY, OF MINNEAPOLIS, MINNESOTA, ASSIGNOR TO JOSEPH S. McCABE,
OF MINNEAPOLIS, MINNESOTA.

CONCRETE-CULVERT MOLD.

1,243,910.

Specification of Letters Patent. Patented Oct. 23, 1917.

Application filed July 24, 1916. Serial No. 110,822.

To all whom it may concern:

Be it known that I, HENRY F. WORLEY, a citizen of the United States, residing at Minneapolis, in the county of Hennepin and State of Minnesota, have invented certain new and useful Improvements in Concrete-Culvert Molds, of which the following is a specification.

My invention relates to concrete culvert molds and has for its object to provide a collapsible inner mold or form which may be quickly assembled or taken down, and which when up will support the weight of the concrete in an efficient and stable manner. In carrying out this object I employ a pair of longitudinal base members upon which are detachably secured a pair of segmental arch-like supports, which supports carry a number of longitudinal cover sheets forming the exterior surface over which the concrete is poured.

The full objects and advantages of my invention will appear in connection with the detailed description thereof and are particularly pointed out in the claims.

In the drawings, illustrating the application of my invention in one form,

Figure 1 is an elevational view of my invention with parts cut away to show the construction of the same. Fig. 2 is a transverse sectional view of a culvert with my apparatus in place. Figs. 3 and 4 are enlarged elevational detail views of the device for locking the supporting members in place showing the parts in relatively altered positions. Fig. 5 is an end view of the device shown in Figs. 4 and 5.

My invention comprises primarily a semi-cylindrical interior mold or form over which concrete may be poured to form an arched channel and is best illustrated in Figs. 1 and 2. A pair of longitudinal base members 10 and 11, preferably formed of angle iron, are provided near the ends with castings 12 and 13 which are rigidly riveted to both flanges thereof. Upon these castings are detachably mounted in a manner to be presently described a pair of arched supporting members 14 and 15 formed by bending an angle iron in an arc of a circle with one of the flanges 16 in the plane of the circle and the other flange 17 positioned at

the inner periphery of the same. Each of the flanges 16 of members 14 and 15 is provided at regular intervals along the outer periphery thereof with a number of angular notches 18, by means of which the cover sheets 19 or members forming the molding surface of the device are held in place. Members 19 are formed of sheet metal cut in long strips of a length equal to the length of the base members 10 and 11, with one of their edges 20 bent at an angle to the body of the same to form a sort of hook extending throughout the length of each strip. These strips are further made slightly concave along their extended surface by slightly bending the body of the strip at the center parallel to an edge thereof, as clearly indicated at 21 in Fig. 2. This concave surface of the strip in conjunction with the turned-over edge 20 has the effect of greatly stiffening the strips to effectively support the mass of concrete which is placed upon these cover sheets or strips. The manner of applying the strips 19 to the supports is almost self-evident from the drawings. The strips are hooked into the notches 18 in said supports by means of the turned-over edges 20, the strips being first placed on the lowest notches and then on succeeding notches until all but a central space at the top has been covered, each strip overlapping the previously-positioned strip. This last space is closed by a concave strip 22 formed without a hooked edge, which strip has attached to its underside a pair of blocks 23 which fit into rectangular notches 24 in the flanges 16 of the arched supports 14 and 15. Blocks 23 are themselves provided with similar notches by means of which the supports and said upper strip are held from movement in a longitudinal direction. These blocks are preferably of a width equal to the space between the turned-over edges 20 of the last two strips, so that the last strips are securely held in place.

The means for detachably mounting or securing supports 14 and 15 to castings 12 and 13 are shown in detail in Figs. 3, 4 and 5, and since these devices are identical in construction only that used in conjunction with support 14 and base member 10 will be described in detail. Casting 12 is formed

with a vertical wall 26 positioned a short distance from the edge of the angle base members 10, from which wall issues a web-like structure 27 terminating in a downwardly-projecting hook 28 situated in a longitudinal plane. Support 14 is provided with a rectangular aperture 29 through which the hook 28 is adapted to pass when the support 14 is placed in position as shown in Fig. 3. A dog 30 is provided with a notch 31 adapted to engage the under side of the flange 16 at 32 to raise said flange against the hook 28 and firmly hold the same in place. This dog is mounted on a pin 34 which passes through a vertical slotted hole 35 therein, which pin is secured to a depending portion 36 of the hook 28 and to the wall 26. Each of the dogs 30 on each of the base members 10 and 11 is provided at its lower extremity with a bifurcated portion 37 by means of which it is pivoted to a longitudinally-extending bar 38. When the bar is drawn forward dog 30 is caused to take the position shown in Fig. 3, with the portion 37 substantially under the end of the flange 16. Thus the whole weight of the form and the concrete poured thereon is held directly by the base member 10 through the dog 30 without any intermediate pivotal support. When bar 38 is shifted backward dog 30 slides on pin 34 and is shifted to the position shown in Fig. 4, whereby the flange 16 is disengaged from the hook 28. To facilitate the downward motion of said flange the upper portions 39 and 40 of hook 30 and wall 26 are made inclined so that the support slides smoothly out of its previous position. It will here be noted that the movement of dog 30 is such that the flange 16 is actually discharged from engagement with hook 28. In this manner a positive action is secured which causes the mold or form to completely collapse when said bar 38 is actuated.

In Fig. 1 is shown a device for actuating the bar 38. An L-shaped casting 41 is riveted to angle iron 10 near the front end and is bored to receive a spindle 42 constrained to purely rotational movement therein by a collar 44, hand wheel 43 and with which said spindle may be rotated. Spindle 42 is threaded at its free end and is adapted to screw into a threaded block 45 to which the end of bar 38 is firmly secured. In this manner the supports are simultaneously disengaged to cause the whole mold to collapse at one time, or are simultaneously clamped in place.

The manner of operation and use is very simple. A ditch 46 is dug of a width equal to the exterior width of the culvert. A flat or concave bottom 47 is then cast and allowed to set and the mold erected and positioned upon this bottom. Concrete is

now poured or placed about the mold at 48 as clearly shown in Fig. 2 and allowed to set, after which the mold is removed and again erected. Two such molds, as described, may be conveniently used together if desired, thus increasing the length of culvert cast at one time.

By employing arched supporting members of different radii having the notches in the peripheries of the different members equispaced, different sizes of culverts may be easily and quickly formed with one outfit employing the same base members and the desired number of cover sheets or strips. In certain cases when a culvert of large dimensions is being formed it is found that the form-supporting members 14 and 15 are not held sufficiently rigid in place by the hook member 28 and the dog 30. In such cases I employ an additional set of braces 50 which have shouldered ends adapted to be placed into corresponding depressions in the base members 10 and 11 and in the flanges 17 of the supporting members 14 and 15. Any longitudinal stresses imparted to either of the members 14 and 15, which are usually in a direction toward the front of the mold, are hence counteracted by these braces 50 and by the blocks 23 on the upper cover strip 22.

95

I claim:

1. A molding device comprising a base member, a form-supporting member having an aperture in one end thereof, a casting secured to said base, a downwardly-projecting hook issuing therefrom and adapted to coöperate with said aperture, means mounted on said casting acting upon said supporting member for holding the same locked in position under said hook, and a form positioned on said form-supporting member.

100

2. A molding device comprising a base member, a form-supporting member having an aperture in one end thereof, a casting secured to said base, a downwardly-projecting hook issuing therefrom and adapted to coöperate with said aperture, a dog mounted on said casting acting upon said supporting member and said base for holding the supporting member locked in position under said hook and for directly transmitting the weight upon the supporting member to the base, and a form positioned upon said supporting member.

105

3. A molding device comprising a base, a clamping device secured to said base, a form-supporting member adapted to be held in place by said clamping device, said device including means for releasing said support and for positively ejecting said support from said clamping device, and a form positioned on said form-supporting member.

120

4. A molding device comprising a longi-

130

tudinal base, a pair of clamping devices secured one at each end to said base, a pair of form-supporting members adapted to be held in place by said clamping devices, said devices including means for releasing said supports and for positively ejecting said supports from said clamping device, means for simultaneously actuating said releasing

and ejecting means, and a form positioned on said supports.

In testimony whereof I affix my signature in presence of two witnesses.

HENRY F. WORLEY.
